Primary Examiner — Doris Clark(74) *Attorney, Agent, or Firm* — McDonnell Boehnen Hulbert & Berghoff LLP(57) **CLAIM**

The ornamental design for a ceiling panel system, as shown and described.

DESCRIPTION

FIG. 1 is a top perspective view of a ceiling panel system;

FIG. 2 is a bottom perspective view thereof;

FIG. 3 is a top view thereof;

FIG. 4 is a bottom view thereof;

FIG. 5 is a front elevation view thereof, and the rear elevation view is identical to the front elevation view; and, FIG. 6 is a right side elevation view thereof, and the left side elevation view is identical to the right side elevation view. The broken lines depict portions of the ceiling panel system that form no part of the claimed design.
